EXHAUST HEATER

Eben Hunter Carruthers, Seneca Falls, N. Y., assignor to Goulds Pumps, Inc., Seneca Falls, N. Y., a corporation of New York

Application May 14, 1936, Serial No. 79,627

11 Claims. (Cl. 257—2)

In the reclaiming of spent lubricating oils, transformer oils, and the like, it is customary to subject these oils to a treatment comprising a centrifuging operation which has for its purpose the separation of the oil from associated contaminating materials, such as water, carbon, or the like, the centrifuging process throwing the contaminants into an outer zone of the centrifuge, from which they may be discharged, while the oil, being lighter, remains in the inner compartment or section of the centrifuge, so that the oil and the contaminants are separately discharged from the centrifuge.

In order to treat the oil in this manner effectively, it is necessary that its viscosity be sufficiently low so that its fluidity will permit the ready separation of the oil and contaminants. However, in view of the fact that many lubricating oils, transformer oils, Diesel engine fuel oils, and the like, are of normally relatively high viscosity, it becomes necessary to preheat them to impart thereto the necessary degree of fluidity for effective centrifugal separation; and the oils must be at a suitable temperature in the centrifuge in order for the treatment to proceed in a satisfactory manner.

The present invention has for its object, therefore, the provision of a heater for use in heating lubricating oils for Diesel engines and the like preparatory to centrifugal purification of these oils, in which heater there is utilized the heat from the exhaust of the engines, and in which the drawbacks and disadvantages both as to electric heaters and heaters using sources of heat other than electricity, are obviated.

A further object of the invention is to provide a heater of this type, utilizing the waste gas from a Diesel engine as the heating medium, which will prevent overheating of the oil, which will control in an effective and efficient manner the heat interchange between the gases and the oil being treated, which will be easily accessible for cleaning, and which will be composed of a relatively few simple parts which have a minimum likelihood for getting out of order, but which if they do can be replaced with ease.

Other objects of the invention will in part be obvious and will in part appear hereinafter. The invention accordingly comprises the features, properties, and the relation of elements which will be exemplified in the construction herein-after described and the scope of the application of which will be indicated in the claims.

For a complete understanding of the present

invention, reference may be had to the accompanying drawings, wherein

Fig. 1 is a diagrammatic assembly, partially in section and partially in elevation of the apparatus of the present invention as used in connection with a centrifugal purifier.

Fig. 2 is an exterior end view of the present improved unit, the view being taken exteriorly of the casing thereof and illustrating one way of mounting the heater unit in position for service.

Fig. 3 is a sectional elevation of the improved heater unit embracing the features of the present invention, the view showing the gas-control valve in closed position and the circulation of the heating gas with the valve in the said closed position, the view being taken on the line 3—3 of Figure 2.

Fig. 4 is a sectional elevation of the heater unit taken at approximately right angles to Fig. 3, the gas manifold being shown in section and the gas-control valve in open position, the casing of the heat exchange element being partially broken away to show the circulation of the heating gases when they are flowing in heat-exchange relation with the oil being treated.

Fig. 5 is a view of the outside of the housing for the gas-valve control mechanism.

Fig. 6 is a sectional elevation of the valve control mechanism, the view being taken on the line 6—6 of Fig. 5, the thermostat housing being partially broken away.

Fig. 7 is also a sectional elevation of the valve-control mechanism, the view being taken on the line 7—7 of Fig. 5, or Fig. 6 the solenoid housing being shown in elevation.

Fig. 8 is a sectional view through the heat exchanger taken on the line 8—8 of Fig. 3, looking in the direction of the arrows.

Fig. 9 is a sectional plan view of the heater unit shown in Figs. 3 and 4, the view being taken on the line 9—9 of Fig. 3, looking in the direction of the arrows.

Referring more particularly to the drawings, it will be seen from Fig. 1, that the improved mechanism indicated at A may be interconnected with a centrifugal purifier B, so that the oil being treated in the purifier may be circulated through the heater for reducing the viscosity of the oil sufficiently for enabling it to be purified in the centrifugal purifier B.

The centrifugal purifier B is of a usual construction, which need not be described, and it has associated with it a gear pump 10 of any suitable type for handling the oil to be treated, this oil being spent lubricating oil, fuel oil, or the like, as previously mentioned above. It enters

the system through the intake pipe 12, which receives the oil from any supply thereof, which may be a storage tank, the oil flowing through the pipe 12 being cold and of relatively high viscosity.

5 The intake pipe 12 communicates with the suction side of the pump 10, through a strainer 14 positioned in a housing 16. As indicated by arrow 18 the oil passes through the outlet 20 of the housing 16, this outlet registering with intake 22 of the pump 10. Flange 24 affords connecting means between the strainer housing 16 and pump housing 26 of the pump 10.

10 The pressure side of the pump 10 communicates through passage 28 with pipe 30, the oil being forced therethrough under pressure of the pump, as indicated by the arrow 32.

15 The pipe 30 enters housing 34 of the valve control mechanism, which mechanism will be described in detail hereinafter, the pipe 30 communicating with the intake port 36 of the housing 34. A pipe 38 connects the housing 34 with the heat exchanger 40, wherein the oil is caused to travel in a spiral path 42, while being heated, as will be explained in detail hereinafter.

20 25 30 35 40 As will be seen from Fig. 1, the arrows 44 and 46 indicate the direction of flow of the oil into the heat exchanger 40, the end 48 of the heat exchanger receiving the intake pipe 50. As the oil spirals through the heat exchanger 40 in the direction indicated by the arrows 52, it becomes heated and lowered in viscosity, and it flows from the heat exchanger through an outlet passage 54 into the housing 34 of the valve control mechanism, thence out, as indicated by arrows 56 and 58, by way of outlet 60 into a pipe line 62 which leads to the centrifugal purifier B.

45 The pipe line 62 branches, as indicated at 64, one branch 66 communicating with the strainer housing 16, the other branch 68 leading to the centrifugal purifier B.

50 55 60 65 A valve 70 is positioned in the branch 68, for controlling the direction of flow of the oil through the respective branches 66 and 68, closing of the valve 70 causing the oil to be by-passed through the branch 66, then into the strainer 14, as indicated by the arrow 72. On the other hand, when the valve 70 is opened, the heated oil may pass into the branch 68, as shown by arrow 74 and flow into the centrifugal separator B by way of pipe 76.

70 75 80 85 90 It will be seen also that the branch 66 is controlled by a relief valve 78 comprising a spring-pressed ball valve member 80 which is normally maintained seated over the outlet of the branch 66 by pressure of a spring 82, which spring is compressed between the valve member 80 and the spring adjusting screw 84 which is threadedly mounted in the valve housing 86. The compression of the spring 82 is adjusted by manual adjustment of the screw 84, a handle 88 being provided for this purpose. A gage 90 indicates the pressure on the circulating oil.

95 The heated oil may therefore be recycled through the heater or through the purifier B, selectively.

100 105 110 115 120 The pump and associated parts being of the usual type, the construction of the heat exchanger and valve control mechanism may now be described.

125 130 135 140 145 The casing 40 (Fig. 3) is a generally cylindrical housing provided with a closed end 48 which receives the pipe 50 as has been described above. The other end of the casing 40 is provided with a flange 92 and an outlet 94 which communicates with the housing 34 of the valve control mechanism to be described hereinafter.

150 155 160 165 170 The casing 40 receives a metallic casting 96, which is preferably made of aluminum because of its lightness and high heat conductivity, although it may be made of any other desired metal. This casting 96 is in the general form of a hollow cylinder having a closed end 98. The interior of this casting 96 is provided with longitudinally extending corrugations or fins 100, which are parallel to the axis of the cylinder 96, and are of a shape to allow easy cleaning. Externally, the 175 cylindrical casting 96 is provided with a continuous spiral groove 102, which may be formed either as a single or multiple thread and which, in conjunction with the tubular casing 40, which fits closely over the outside diameter of the 180 casting 96, forms the spiral path 42 through which the oil travels, as mentioned above. The open end of the cylinder 96 is provided with a flange 104 which is adapted to rest on the flange 92 of the tubular casing 40.

185 190 195 200 205 As the oil flows in a shallow or thin stream through the spiral groove 102, it becomes heated by heat conducted through the casting 96 from hot combustion gases passing through the interior of the casting 96. These gases are brought into heat exchange relation with the oil by way of a gas manifold 106, which comprises a cylindrical casting 108 having a flange 110 which is bolted to the flange 104 of the heat exchanger 96 and the flange 92 of the casing 40 by suitable bolts 210 215 220 225 230 235 240 245 250 255 260 265 270 275 280 285 290 295 300 305 310 315 320 325 330 335 340 345 350 355 360 365 The valve 126 is of somewhat smaller diameter than the inner diameter of the heat exchanger casting 96, so that the valve 126 can slide into and out of the heat exchanger casting 96, the movement of the valve 126 being guided by the spacers 136 which slide in the depressions 138 between the fins 100 on the inside of the heat exchanger casting 96.

One end of the tubular valve 126 is provided with an annular flange 140 which is secured to the valve 126 in any suitable manner, this flange 140 being of sufficient diameter to cover the annular space 142 between the tubular valve 126 and the inside of the heat exchanger casting 96, when the valve 126 is closed.

The flange 140 is provided with an opening 144 through which extends a valve stem 146 to which are secured radially extending arms 148 near the end of the stem which is within the tubular valve 126. These arms 148 are adapted to engage the underside of the flange 140 as the valve stem is moved outwardly relative to the valve 126 for shifting the valve to open position, and as the valve stem is moved inwardly relative to the valve 126, the arms 148 abut against the collar 137 for shifting the valve 126 to closed position.

When the valve 126 is closed, the flange 140 engages the end surface of the heat exchange casting 96, thus blocking flow of gases through the heat exchanger, while when the valve 126 is in open position, it has shifted relatively to the casting 96 so that the flange 140 has moved away from the end surface of the casting 96 until the flange 140 abuts against the inner end or port 97, of the deflector 116, thus registering with the deflector and passing the gases into the valve 126, as the by-pass passage for the gases through the manifold is now cut off.

Thus, when the valve 126 is open, the hot gases pass through this tubular valve, through the opening between it and the end 98 of the casting 96, and thence through the space 142 between the valve 126 and the heat exchanger casting 96, the gases giving up their heat to the colder oil passing through the groove 102 by conduction of the heat through the casting 96.

In order to facilitate and to guide the flow of gases around the end of the tubular valve 126 and between the end 98 of the casting 96, the latter is provided with a projecting guide or deflector 150 which has a convex surface for deflecting the gases around the end of the valve tube 126.

It will be seen that the valve stem 146 extends through the manifold casting 114, which casting is provided, of course, with a suitable opening for the passage of the valve stem 146.

This valve stem 146 is provided intermediate its ends with a cup-shaped retaining member 156 which is secured to the stem 146 and receives a coiled spring 158, which is compressed between the retaining cup 156 and the top 160 of the spring housing 162. This spring housing 162 is provided with a flange 164 which may be flush with the flange 118 of the manifold casting 114, which may be provided with an annular groove or recess 166 in which the flange 164 of the spring housing may be received and sealed to form a gas-tight seal 152, which may be retained by means of bolts 165. The closed end 168 of the spring housing 162 forms a guide for the valve stem 146, and the cover 160 is provided with a boss 170 which acts as a retainer and guide for the spring 158. The spring housing 162 is pro-

vided with a flange 172 to which the cover 160 is bolted by means of bolts 174. The boss 170 also serves as a guide for the valve stem 146, which valve stem is enclosed in a sleeve 175 which may be renewed readily when worn, this sleeve and valve stem extending into the opening 176 provided in the cover 160 for this purpose. The end of the valve stem 146 is provided with a nut 178 which acts as a retainer for the sleeve 175.

The spring 158 normally urges the arms 148 towards the collar 137 in the valve 126, to tend to hold the flange 140 against the end of the casting 96.

The operating mechanism for the valve 126 includes a lever 180 which extends through the spring housing 162. This lever 180 is fulcrumed on a lug 182 upstanding from the flange 164 of the spring housing, and is connected to the spring retaining cup 156 by a yoke 184 and pins 186 which connect the yoke to the cup 156. The fulcrum lug 182 is adjacent to one end of the lever 180, the other end of the lever being provided with an abutment 188 which engages with the end piece 190 of the piston rod 192 of a valve actuating piston 194 (see Fig. 6), so that as the rod 192 is lifted, as viewed in Fig. 3, it will lift the abutment end 188 of the lever 180, as viewed in Fig. 3, in a substantially straight line movement, thus lifting the cup 156 and valve stem 146 against the pressure of the spring 158, thereby bringing the arms 148 of the valve stem 146 into engagement with the flange 140 of the valve 126, thus moving the valve 126 from the closed position of Fig. 3 to the open position of Fig. 4, thus allowing hot gases to flow through the heat exchanger to heat the oil passing along the spiral groove or thread 102.

Conversely, when the piston rod 192 falls, as viewed in Fig. 3, the pressure on the spring 158 is relieved and the spring moves the valve stem 146 so as to disengage the arms 148 from the flange 140 and engaging the arms with the collar 137, thus allowing the valve 126 to shift into closed position to cut off the flow of the gases through the heat exchanger.

It will be seen from Fig. 6 that the end piece 190 of the piston rod 192 is in effect, a sleeve which is fitted over the end of the rod 192, the piece 190 forming an abutment member for engaging the abutment 188 on the lever 180. The abutment 190 is hollow and is internally threaded as indicated at 196 for intermeshing with threads 198 on the piston rod 192, thereby enabling the abutment to be adjusted longitudinally of the stem for effecting any desired adjustment of the amount of movement of the lever 180. A lock nut 200 holds the abutment 190 in the desired adjusted position.

The piston 194 is essentially a fluid actuated piston which is secured to the rod 192 by a nut 202 and which operates in cylinder 204 in the housing 34.

The intake 208 of the housing 34 is bossed, as indicated at 210 for connecting with a corresponding boss 212 (Fig. 3) of the fluid outlet 54 of the heat exchanger. The housing 34 and the cylinder 204 are closed by a flanged cover 214, which is bolted to the housing 34 by bolts 216. The cover 214 forms a guide for the rod 192 and is provided with a recess 218 into which is placed packing 220 for preventing leakage of oil around the piston rod 192. The cover 214 has an extension 222 which is exteriorly threaded as indicated at 224 for receiving a cap nut 226 which

closes the recess 218 and forms an additional guide for the rod 192.

The piston 194 is a fluid operated piston the action of which is controlled by the temperature of the oil flowing through the system, the flow of which oil is controlled in turn by a piston valve 228 operating in a cylinder 230 in a housing 232. The cylinder 230 is in communication with the cylinder 204 by a passage 234 which extends from a port 235 in the upper part of the cylinder 230 to the port 237 in the lower part of the cylinder 204 so as to be beneath the piston 194. The piston valve 228 is provided with upper and lower flanges 236 and 238, respectively, which are interconnected by the valve body, and is provided with an internal channel 242, extending longitudinally through the valve and communicating with a space 244 in which is positioned a spring 246 which presses against the valve 228. Between the flanges 236 and 238 of the valve 228 there is an annular space 248 with which connects the oil line 30 from the discharge side of the pump 10 (Fig. 1) and an outlet 250 from the space 248 connects with the pipe 38 leading to the intake port 252 of the heat exchanger.

The spring 246 is seated between the flange 254 and the valve 228, bearing upon the valve flange 236 to tend to maintain the valve 228 pushed towards the port 255 in the end of the cylinder 230. A small opening 256 in the valve 228 connects the valve channel 242 with the space 258 between the valve flange 238 and the end closure 260 of the cylinder 230, which closure contains the port 255. The purpose of this construction will become apparent hereinafter.

Now, referring back to the cylinder 204 in which the valve piston 194 operates, it has been said that the intake port 208 connects with the outlet 54 for the exchanger. This means, therefore, that heated oil will pass from the exchanger through port 208 into a space 262 behind the valve piston 194. This space 262 communicates with a space 264 in which is located a thermal-responsive element 266 which may be of any desired standard construction and which may be set to operate at any desired temperature. The space 264 communicates with the space 244 by way of a port 268 which passes through the flange 254. The hot oil line 62 connects the space 244 with the centrifugal purifier B (Fig. 1) and with the intake side of the pump 10, whereby the heated oil may be circulated through the purifier, or recycled through the system as may be desired.

The thermostat 266 operates a switch indicated at 270 enclosed in a housing 272, which switch, as is shown in Fig. 5, is in electrical circuit through conductors 274, 276, 278, 280 and 282 with a solenoid valve 284 (Fig. 7), the solenoid of which (not shown) is enclosed in housing 286. Operating power is taken from a power line 288 (Fig. 5) to the respective sides of which are connected the conductors 276 and 278. A manual switch 290 may be included in the circuit, it being understood that this switch is closed while the apparatus is in operation.

The solenoid valve 284 operates in a space 292 which is in a housing 294 and which communicates with the space 248 between the valve flanges 236 and 238, by a connection 294'. The solenoid valve 284 is arranged to open and close a port 296 which is connected by a pipe 298 with the port 255 under the piston valve 240. The port 296 extends through a flange 300 which forms a seat for the valve 284.

In operating the present system, the oil be-

ing treated, such as lubricating oil, fuel oil, or other high viscosity oil, is fed into the system through the supply pipe 12 and through the pump 10 by way of the filter screen 14. The pump 10 forces the oil through the pipe 30 into the space 248 between the flanges 236 and 238 of the piston valve 228 which is yet in closed position as shown in Fig. 7 through action of the spring 246, and flowing around the valve 228 it fills the pipe connection 294' and the space 292 around the solenoid valve 284, which is still seated or closed, as indicated in Fig. 7. Therefore, the oil cannot reach the by-pass pipe 298, but it will flow out from the space 248 by way of port 250 into the pipe 38 which connects with the intake port 252 in the closed end 48 of the casing 40 of the heat exchanger.

The oil as it passes into the heat exchanger follows the spiral 102 through the exchanger casing 40 until it comes to the outlet 54, passing therethrough into the intake 208 of the valve piston housing 206 (Fig. 6), and passes around the thermostat 266, thence into space 244, and thence through the pipe 62 back through the pump 10, it being understood that the valve 70 is closed while the oil is recycling. This circulation of the oil is maintained continuously, as long as the pump 10 is operating.

At this stage of operation, since the by-pass pipe 298 is empty and the valve 228 is in position against the end piece 260 of the cylinder 230, see Fig. 7, the flange 236 of the valve will close communication between the chamber 248 between the valve flanges 236 and 238 and the port 235 (Fig. 6), thereby closing communication between the chamber 248 and the cylinder 204 in front of the valve piston 194. Therefore, the cylinder 204 is empty of oil, and valve piston 194 will be at its closest position to the cylinder head 203 of the cylinder 204, the piston 194 being held in that position by the pressure of spring 158 acting on the retainer cup 156 (Fig. 3), which pressure is transmitted to the piston rod 192 through the lever 180 by way of its yoke connection 184 with the cup 156. The spring 158 also holds the arms 148 on the valve stem 146 out of engagement with the flange 140 of the gas valve 126, the arms 148 being pressed against the collar 137, the valve 126 thereby being held closed as in Fig. 3 so that hot gases, such as hot combustion gases entering the manifold 106 through the intake 122 pass out immediately through the outlet 128 without being enabled to pass through the valve 126. Therefore, the oil flowing through the spiral groove 102 cannot be heated, but as has been said before this oil although cold is continuously circulated as long as the pump 10 is operating.

Now, let the manual switch 290, Fig. 5, be closed. The thermostat 266, which is set to operate at a predetermined desired elevated temperature, say 180° F., is still immersed in cold oil. The solenoid valve circuit will be energized, opening the solenoid valve 284, and allowing oil from the space 248 to flow into the by-pass pipe 298. This flow is greater than the counter-flow of oil through the small opening 256 in the piston valve 238, so that this piston valve 238 will be lifted against the pressure of the spring 246, thus opening the passage 234, as shown in Fig. 6, and admitting oil in front of the valve piston 194, moving it and the rod 192 against the lever 180 (Fig. 3) and, overcoming the pressure of the spring 158, causes the arms 148 to engage the flange 140 of the valve 126, opening the latter as shown in Fig. 4 and allowing the hot gases to pass therethrough.

and around in the space 142 between the valve 126 and the casting 96, thus heating the oil by heat conduction through the casting 96.

The oil thus heated passes around the thermostat 266 until it is brought to required temperature, when the thermostat 266 operates to break the circuit through the solenoid valve, which immediately closes, cutting off oil flow into the pipe 298. The release of oil pressure in pipe 298 relieves the pressure behind the piston valve 228, allowing the spring 246 to move the valve, the oil in the portion 258 of the piston valve cylinder being displaced through the opening 256 in the piston valve by movement of the valve.

When the piston valve 228 thus moves, its flange 236 passes the port 235 and puts the passage 234 in connection with the discharge from the heat exchanger, thus destroying the pressure difference across the valve piston 194, thus enabling the spring 158 to act on the lever 180 to push the piston 194 towards the head 203 of the cylinder 204, allowing the gas valve 126 to return to the closed position of Fig. 3. The flow of gas, as indicated by the arrows of Fig. 2, by-passes the heat exchanger and flows through the gas manifold 106 only. The oil flow continues the same.

The thermostat 266 may be of any standard construction such as a liquid thermostat containing a liquid which boils in the thermostat at a definite temperature, so that when the thermostat reaches that temperature, the liquid vaporizes and breaks the circuit through the solenoid valve 284. When the oil cools, the volatilized liquid in the thermostat recondenses, so that the thermostat becomes automatically operative. This is a well-known type of thermostatic switch, and requires no further description.

It may be pointed out at this point that in prior heaters of this general type using electric heat, there is a tendency for oil to carbonize due to the high temperatures of the surfaces of the heater elements. These high temperatures not only carbonize the oil but bake the carbon on the heater elements, reducing the heat transfer and efficiency of the heater. Also, where moving oil is being heated, there are likely to be "film effects" due to the presence of a stationary film of oil between the moving oil and the heating elements, which film of oil acts as a high heat insulator, as well as tending to become carbonized by overheating.

In the present construction, however, there are of course no electric heating elements, and the spiral groove 102 minimizes film effects by producing a rapid and turbulent flow of oil around the heat exchange cylinder 96, which prevents the formation of stationary film by breaking up such film, thereby minimizing possibility of local overheating of the oil.

Furthermore, the present construction is characterized by the fact that the parts may be readily disassembled for convenient access to the various parts for purposes of cleaning, and the surfaces of the heat exchanger that are exposed to the oil and gases are all arranged for easy cleaning. Thus by removing bolts 112, the manifold casing 106 may be removed, and access had to all parts of the heat exchanger; and in this connection it may be noted that the inside fins 100 of the heat exchange casting 96 are parallel to the axis of the casting to allow easy cleaning.

With reference to the improved structure herein described, it will be seen that it possesses definite advantages with respect to the various parts of the construction.

Thus, with regard to the heat exchanger itself, it will be seen that it is made up of two parts with only one oil-tight joint to be maintained; that the continuous helical oil passage formed by the thread-like groove 102 on the outside of the exchanger casting 96 insures a flow of fluid over the entire surface, eliminating "dead" areas where carbon or other solid matter which may be present in the oil might collect; that removal of the exchanger shell 40 exposes the entire oil passage surface for quick and easy cleaning; that the design of the exchanger allows the ratio of gas surface area to oil surface area to be made most suitable for results desired; that the large area of fluid contact with the assured rapid movement of the fluid prevents overheating of the oil film on the exchanger threads with consequent elimination of carbon formation when oils are being heated.

With regard to the manifold, the manifold casting 108 is provided with a number of ports and bosses, any of which can be used either for inlet or outlet piping or for mounting to the support plate. This allows the piping to be arranged in any manner meeting the requirements of any specific plant arrangement. When the manifold cover plate 114 is withdrawn, the deflecting elbow 116, valve stem 146, and valve 126 are withdrawn with it, thus leaving a clear opening into the inner surfaces of the heat exchanger casting 96. Thus the exchanger shell 40 alone, or both shell and exchanger body, may be detached from the manifold without disturbing the piping with exception of pipe 38, or the mounting of the heater.

With regard to the gas valve 126, it will be seen that it has no sliding seats that might be fouled by carbon or soot deposits. With the valve in the "nonheating" position, the flow of gas through the piping to and from the heater is not stopped, this keeping the pipes and manifold hot all the time the heater is in operation, whereas stopping the flow of gas intermittently would cause cooling with consequent formation of corrosive liquids in the gas passages.

With regard to the valve operating mechanism, it will be seen that it is simple and positive in its action, and closely responsive in its operation to temperature changes of predetermined amounts in the oil; and also the valve operating mechanism incorporates automatic safety features in allowing the gas valve to return to non-heating position by the automatic thermal switch control, or by breaking of the electric circuit to the thermostatic switch, or by failure of oil circulation through the exchanger.

It will be seen that the entire discharge from the heater may be returned to the suction side of the pump 10 through the relief valve 80, or part of it may be delivered to the purifier B by opening the valve 70. When the valve 70 is opened, and the hot oil flows into the purifier B, an equal amount of oil enters the system through the supply pipe 12 for treatment, so that a quantity of oil equal to the whole pump capacity is continually circulated through the heater while the pump is running.

It will be understood, of course, that all joints and connections between the various parts of the construction are rendered gas-tight and fluid tight by the use of suitable gaskets and/or packing, as will be well understood.

While the specific heating medium described herein is hot exhaust gases from the engine, it will be understood that other fluid heating me-

diums may be used, such as for example, hot air or steam, if the conditions of operation render the use of such heating materials to be desirable.

It will be understood, of course, that the invention is not limited necessarily to the specific details of the construction as herein illustrated and described, but that various modifications in the construction may be made without departing from the scope of the invention, it being intended that all matter contained in the above description or shown in the accompanying drawings are to be interpreted as being only illustrative and not in a limiting sense.

It is also to be understood that the following claims are intended to cover all of the generic and specific features herein described, and all statements of the scope of the invention, which, as a matter of language, might be said to fall between; and that it is intended and desired to embrace within the scope of the invention such modifications and changes as may be necessary to adapt it to varying conditions and uses.

What is claimed is:

1. A heater for fluids comprising the combination with means for circulating the fluid, of a heat exchanger through which the fluid flows comprising shiftable means for controlling admission of hot gases into heat exchange relation with fluid passing through the heat exchanger, a gas manifold adapted to admit hot gases to the heat exchanger when the said shiftable means are in position for admitting gases to the heat exchanger and to by-pass the gases when the said means are in position to block admission of gases to the heat exchanger, instrumentalities for operating the said means, including pressure actuated devices for shifting the said means, temperature responsive instrumentalities operable responsively to temperature variations in the fluid of predetermined amounts, and a control valve for controlling the said pressure actuated devices responsive to actuation of the temperature responsive instrumentalities for actuating the said shiftable means in accordance with the temperature variations in the fluid.

2. A heater for fluids comprising the combination with means for circulating the fluid, of a heat exchanger through which the fluid flows comprising a casing, means in the casing for imparting a tortuous path of circulation for the fluid flowing through the exchanger, a shiftable baffle valve disposed interiorly of the said means for controlling admission of hot gases into the said means and in heat exchange relation with fluid passing through the heat exchanger when the said baffle valve is in position for admitting gases to the heat exchanger and to by-pass the gases when the said valve is in position to block admission of gases into the said means, instrumentalities including pressure operated devices for shifting the said baffle valve, valve means for regulating the pressure operating said devices, and thermostatic means for controlling said valve means in response to temperature changes of predetermined amounts in said fluid.

3. A heating apparatus for fluids comprising the combination with a casing of heat exchange instrumentalities within the casing including a hollow cylindrical casting defining a fluid passage between the casting and the casing, a tubular baffle valve within the casting for controlling admission of hot gases into the said casting to admit and to prevent, respectively, flow of gases according to differences in position of the baffle valve, the said valve defining a gas circulation

space between the casting and the valve, an internal abutment in the valve, means adapted to admit gases to the interior of the baffle valve when the valve is in open position and to bypass the gases when the valve is in closed position, instrumentalities for shifting the said valve including a valve stem provided with arms disposed in the valve for engaging the valve to shift the same relative to the casting, a lever connected to the valve stem and a spring urging the stem and arms thereon into disengagement with the valve and into engagement with the abutment therein, the said lever being pivoted for substantially straight-line movement, and interacting valve and thermostatic control mechanism for operating the said instrumentalities responsive to temperature changes of predetermined amounts in the fluid circulating through the apparatus.

4. A heating apparatus for fluids comprising, in combination, a heat exchanger through which fluid to be heated may flow, means for passing a heating medium into the heat exchanger in heat exchange relation with a fluid passing through the heat exchanger, instrumentalities for controlling the passage of the heating medium into the heat exchanger, and mechanism for operating the instrumentalities, the said mechanism comprising a thermostatic switch operable responsively to temperature changes of predetermined amounts in the fluid circulating through the apparatus, a solenoid control valve operated by the thermostatic switch, and valve and piston mechanism operated by fluid pressure transmitted by the said control valve for operating the said instrumentalities for controlling the heating medium for the fluid.

5. A heating apparatus for fluids comprising, in combination, a heat exchanger through which fluid to be heated may pass, instrumentalities for introducing heating gases into the heat exchanger, the said instrumentalities comprising a cylindrical casting having a plurality of ports provided with connecting bosses, an inlet pipe connected to one of the ports, an outlet pipe connected to another of the ports, a manifold casting forming a closure for the heat exchanger and including an intake deflector registering with the intake port and pipe and adapted to direct heating gases into the heat exchanger, a by-pass for the gases through the manifold, and means for directing flow of gases from the intake deflector into the heat exchanger and through the by-pass, alternatively, and means for connecting the heat exchanger to the gas-introducing instrumentalities.

6. A heating apparatus for fluids comprising, in combination, a heat exchanger through which fluid to be heated is adapted to flow, the said heat exchanger having an open end and comprising a casing and hollow casting defining together a fluid passage, a manifold forming a closure for the heat exchanger and including means for introducing a heating medium into the hollow portion of said casing in heat exchange relation with the fluid and, alternatively, for by-passing the heating medium through the manifold when the fluid has been brought to predetermined temperature, means for directing the flow of the heating medium relative to the manifold and heat exchanger, and automatically operated mechanism for operating the said means responsively to temperature variations in the fluid of predetermined amounts.

7. A heating system for fluids, comprising the

- combination with pumping instrumentalities for circulating the fluid, of means communicating with a source of hot waste gases and adapted to pass the said gases in heat exchange relation with the fluid to be heated, a heat exchanger comprising a casing, a casting in the casing defining a fluid passage between itself and the casing, a tubular valve within the casting defining a gas passage between itself and casting and reciprocably movable within the casting for opening and closing the said gas passage, and mechanism for operating the said valve including a thermostat in contact with the fluid heated by the said gases and instrumentalities operatively connecting the said thermostat and mechanism for effecting opening and closing of the valve responsive to predetermined amounts of temperature changes in the fluid while permitting continuous circulation of the fluid through the fluid passage in the heat exchanger independently of the operation of the valve.
8. Apparatus for reclaiming spent lubricating oils and the like, comprising the combination with a pump for circulating the spent oil from a suitable source thereof, of a heater operatively connected with the pump adapted for the oil to circulate continuously therethrough, means for introducing a heating fluid into the heater in heat exchange relation with the oil, means for returning heated oil to the pump for recycling through the heater, and mechanism for controlling flow of heating fluid responsively to predetermined temperature variations in the oil, the said mechanism including a fluid-controlling valve for the heater, a cooperating piston mechanism for actuating the said fluid controlling valve responsively to differences in pressure of the circulating oil thereon, a master control valve for controlling the said pressure, a solenoid for operating the said master control valve, a circuit for energizing the solenoid, and a thermostatic switch in the circuit for automatically making and breaking the circuit through the solenoid responsively to predeter-

mined temperature variations in the circulating oil for correspondingly actuating the fluid-controlling valve.

9. A heater for fluid comprising a circuit including pump means and a heat exchanger, said heat exchanger being connected to a source of hot gases; shiftable valve means for deflecting said hot gases from said heat exchanger; piston means operable by pressure of said fluid for controlling said valve means; and shiftable means for causing said fluid to exert pressure alternately against the opposite ends of said piston means, and thereby to cause said valve means to shift and to deflect said hot gases from said heat exchanger.

10. A heater for fluid comprising a circuit including pump means and a heat exchanger, said heat exchanger being connected to a source of hot gases; shiftable valve means for deflecting said hot gases from said heat exchanger; piston means operable by pressure of said fluid for controlling said valve means; and shiftable thermostatic control means responsive to temperature change in said fluid for causing said fluid to bypass said piston means, and thereby to cause said valve means to shift and to deflect said hot gases from said heat exchanger.

11. A heater for fluid comprising a circuit including pump means and a heat exchanger; said heat exchanger being connected to a source of hot gases and comprising a casing and a hollow casting within said casing and defining therewith an annular space in the path of said fluid; valve means shiftable to direct said hot gases into said casting or deflect the same therefrom; piston means operable by pressure of said fluid for controlling said valve means; and shiftable thermostatic control means for causing said fluid to bypass said piston means, and thereby to cause said valve means to shift and to deflect said hot gases from said heat exchanger.

EBEN HUNTER CARRUTHERS.
